MACHINE FOR PRODUCING HEXAGONAL
MESH WIRE FABRIC

Carl W. Holmquist, Glassport, Pa.

Application August 5, 1935, Serial No. 34,759

14 Claims. (Cl. 140—6)

This invention relates to machines for making wire fabric, and has to do particularly with the manufacture of wire fabric of substantially hexagonal design such as used for fences and for other purposes.

An object of my invention is to improve the operation of machinery of this type by so relating the functioning parts that the twisting of the mesh wires proceeds smoothly and the breakage of the mesh wires, whether due to excessive tension or to other incidental operation of the machine, is reduced to a minimum.

Other objects will become apparent in the course of the ensuing description and will be more particularly pointed out in the appended claims.

In the accompanying drawings which illustrate my invention,

Figures 1 and 1a together show an illustrative embodiment of such a machine in front elevation, the central portion being broken away;

Figure 2 is a view principally in cross-section of the machine, the drive being shown in elevation;

Figure 3 is a view in elevation of a detail;

Figure 4 is a sectional view considerably enlarged of a fragmentary detail of Figure 2; and

Figure 5 is a fragmentary view in elevation of a twister bar, with portions broken away.

In the fabrication of wire fabric of the type above referred to, adjacent mesh wires are twisted together to form hexagonal mesh. There is insufficient stretch in the wire generally employed to provide for the twist; and as the fabrication of the mesh proceeds, there is a creep of the wires into the machine to provide enough wire for the twist. The creeping of the wires past the operating parts of the machine has proved troublesome, not only because of the incidental wear on these operating parts, but also because of the frequent breakage of the wires, which results from the excessive tension thus placed upon the wires.

In accordance with my invention I avoid such excessive tension both by pushing the mesh wires into the machine so far that the portions of the wires intermediate the twisters are formed into loops to provide slack between the twisting devices, and by feeding the mesh wires into the machine frictionally.

A preferred device for frictionally feeding the mesh wires is the capstan shown in the accompanying drawings. This capstan, as shown particularly in Figure 2, receives the wires which pass into the machine beneath a guide roll 7.

The capstan itself includes a roll 8 which is preferably grooved to keep the wires in alignment. Each wire is given at least one turn about the roll 8. The latter is mounted on a shaft 9 and is driven at a somewhat faster peripheral speed than the travel of the wires by intermeshing gears 10 and 11. The gear 11 is, in turn, driven through a coaxial sprocket 13 by the chain 12 which is passed also over a sprocket 16 on the main shaft 14 which carries the main drum 15 of the machine.

The capstan and the main drum are, accordingly, synchronized; but there is, to some extent, slippage of the wires on the drum 8 incidental to the frictional drive of the wires. In other words, if the wires are quite loose on the capstan there is so much slippage on the roll 8 that the feed of wire drops behind the requirements of the main drum 15. This results in greater tension on the wires passing from the capstan to the main drum, thus tightening up the turns or bights of the wires around the roll 8, so that there is less slippage on this roll; and the feed automatically catches up to the rate required by the drum 15. The capstan, accordingly, functions automatically to feed the wires to the drum 15 without much tension, and yet the feed is so dependent upon the speed of rotation of the drum 15 that there is no troublesome slack to become entangled in the machine.

The drum 15, as is customary in this art, includes a plurality of twister bars 18; and as illustrated in Figure 5, the embodiment of twister bar shown in the drawings includes twisters 19 of the slotted gear type. Each twister bar 18 includes opposed members 20 and 21, the member 21 being a slotted plate overlying the recesses 23 and 24 provided in the member 20 for accommodating the rack bar 26 and the twisters 19, respectively. In the embodiment shown, machine screws 27 secure the member 21 to the member 20 so as to enclose both the twisters 19 and the rack bar 26 between them.

The member 20 is extended beyond the member 21 and the twisters 19 to provide guides 29. Inclined guide surfaces 30 thereon slope towards the slots 31 which extend through both the member 20 and the member 21, and are adapted to hold the wires on the opposite sides of the twisters when the latter are rotated by the rack bar 26 to twist and unite the mesh wires in the desired hexagonal pattern. Referring to Figure 4, it will be noted that the outer edge of the member 21 is beveled to fit the undercut portion provided in the member 20, thus locking the two members 55

together when the screws 27 are drawn up tight.

The twisters 19 of one bar 18 are arranged in staggered relation with respect to the twisters both of the preceding bar 18 of the drum 15 and 5 also the succeeding bar 18. Accordingly, the guides 29 are in staggered relation; and when the wires first engage these guides 29 (at the point marked "A" in Figure 2), each wire engages alternate guide surfaces 30 on successive guides 29. 10 Accordingly, in moving down the throats into the slots 31, the wire is deflected toward one end of the machine on the respective guide surface 30 of one bar 18 and toward the other end of the machine on the respective guide surface of the succeeding bar 18. This brings about a zig-zag pattern of the wires ready for the twisting of wires in the same slot 31 to produce the hexagonal mesh which is desired.

In order to push the wires down along the inclined guide surfaces 30 of the throats and into the slots 31, I provide positioning means indicated in general by B. Brackets 35 are mounted on the main frame of the machine and secured in adjusted position by bolts 36. These bolts are received within slots, and when loosened permit the brackets 35 to be adjusted toward or away from the main drum 15 by means of the adjustment screws 38. Such adjustment increases or decreases the amount of slack between twister bars, as will be explained more in detail in connection with Figure 4.

The preferred embodiment of positioning means is shown in the drawings and includes endless carriers 40 of the caterpillar type spaced along the machine. These endless carriers comprise links which travel about pairs of sprockets 42 fixed to a pair of shafts 43. These shafts 43 are driven by gears 44 secured thereto which are driven by gears 45 meshing therewith. The gears 40 are carried by a shaft 46 which is mounted in bearings in the brackets 35, the shafts 43 being mounted in bearings in the same brackets. The shaft 46 also revolves in an adjustable bearing 47 (see Figure 3) which is slidable toward and from the main drum 15 in a slotted mounting 49 on the main frame. The position of the bearing 47 in the slotted mounting 49 is fixed by the adjusting screw 50; so that as the brackets 35 are adjusted inwardly and outwardly, the bearing 47 5 may be adjusted relative to the main frame so as to provide a backing or support on the main frame for the driven end of the shaft 46. The pitch lines only of the gears 44 and 45 are shown in Figure 3. On the end of the shaft 46 thus backed or supported is a sprocket 48 driven from the sprocket 16 on the main shaft by the chain 12. A takeup roller (not shown) cooperates with the chain 12 to take up any slack therein.

Each link of each endless carrier 40 is secured to or is integral with a wire engaging element 53 extending lengthwise of the rows of twisters. In the preferred embodiment shown herein, these wire engaging elements take the form of angle bars having a base flange connected to the links 65 of the endless carriers and the other flange extending from the carriers to engage the wires and push them along the guide surfaces 30 into the slots 31 (thus forming the hexagonal pattern) and depress the portions of the wires intermediate the rows into loops of slack between the twisters 19.

Referring to Figure 4, the wire shown entering the machine at the bottom of the figure has already slid down an inclined guide surface 30 of the lowermost bar 18 of the figure and is about

to be pushed by the corresponding lowermost element 53 down the slot 31. In order to follow the same wire through a number of rows of the main drum 15, the section is not taken all in the same plane, but zig-zags from a twister in one row to a staggered twister in the next row. It should be borne in mind therefore that the wire extends diagonally from the lowermost bar 18 to the bar next above, and so on around the drum.

Following along the wire, it will be noted that it has been depressed into the bottom of the slot of the second bar 18; and the second element 53 has started to depress the portion of the wire on beyond the second bar. The third and fourth elements 53 have formed full loops for slack between the adjacent twisters 19; and the fifth element has started to move out from interengagement between adjacent twister bars 18; while the last element 53 has withdrawn completely from contact with the wire. Here, I call attention to a further important feature of my invention, namely, the timing of the twisting to come just as the elements 53 are withdrawn, so as to twist the wires while the slack is available. This feature will be discussed more in detail in connection with the operation of the twister bars themselves.

It will be noted at this point, however, that by means of the screws 38 and 50, the positioning means B may be moved in or out relative to the main drum 15, thus bringing about interengagement between the bars 18 and the elements 53 to a greater or less extent. Greater interengagement, of course, brings about further depression of the intermediate portions of the wires to give more slack, and vice versa. In order that the elements 53 may move into and out of interengagement with the bars 18, the front and rear of the extremities of the bars 18, and particularly of the guides 29, are tapered so that there is no interference due to such interengagement.

The main drum 15 is carried by the shaft 14 which is mounted in bearings 55 and 56 in the main frame of the machine. A motor 57 is connected by a belt drive 58 to a worm gear speed reducer 59, and by a belt drive 60 to the drive connections 61 for the takeup 62. The connections to the takeup include a friction clutch 63, so that as the diameter of the bundle on the takeup increases, slippage in the friction clutch takes care of the resulting slowing down in the rate of angular rotation of the bundle. The approximate maximum size of bundle is indicated in chain lines in Figure 2. A pinion 64 in mesh with a gear 65 on the main shaft 14 of the machine extends laterally from the speed reducer 59 and is driven through the same from the motor 57. The main shaft, as above mentioned, carries a sprocket 16 which drives the sprocket chain 12.

The twister bars 18 are secured on the periphery of the drum 15 in such relation that, as above pointed out, the twisters 19 are in staggered relation. If desired, intermediate line wires may be incorporated in the fabric, and such intermediate wires are fed into the machine in alinement with the slots 31 and with slots cut through the centers of the guides 29. These line wires have a straight path through the machine, as is clear from the arrangement shown in Figure 1. The twister bar shown in detail in Figure 5 omits the slots in the guides 29, and is for use where no intermediate line wires are to be incorporated.

The rack bars 26 mesh with the slotted gear type twisters 19, and are cam operated so as to impart a plurality of complete revolutions to the twisters so as to give the twist to the mesh wires.

in forming the fabric. The twisters herein are slotted gears, the slot in the gear registering with the slot 31 when the wires are being pushed down into these slots at A. After the plurality of complete revolutions above referred to, the rack bars 26 retain the twisters in such position that the slots in the gears register with the slots 31 until the wire fabric leaves the drum 16 at the point C. The wire fabric then passes beneath the guide 10 roll 66 to the take-up 62.

The cams for operating the rack bars 26 are at the opposite ends of the drum. The stationary tracks 68 and 69 are mounted on pedestals 70 and 71, respectively, secured to the main frame 15 of the machine; and with each of these tracks cooperate opposed cam plates 72 and 73. The rack bars are provided each with an actuating element 74, alternate elements (actuating alternate rack bars) being at one end of the machine 20 and cooperating with the same track 68, and the remaining elements 74 being at the other end of the machine and cooperating with the cam track 69. Each element 74 carries on a stud a cam roller (not shown) which is confined between the 25 cam plates 72 and 73 so as to follow the respective cam track and reciprocate the rack bar to which it is connected. The actuating elements 74 are reciprocable within housings having cover plates 75 secured in place by screws 76. Each actuating 30 element 74 is connected to the respective end of its rack bar by an adjustable connection 77 similar in function to a turnbuckle. The cam tracks 68 and 69 are so shaped as to reciprocate each rack bar 26 after the wire fabric has left the drum 35 at the point C and before the wires are pushed down the guide surfaces 30 into the slots 31 upon being fed in at the point A.

The relation of the cam tracks 68 and 69 to the positioning means B is an important feature 40 of my invention. If the rack bars 26 are reciprocated before the elements 53 start to move out of interengagement, the twisters 19 start to twist the mesh wires before the necessary slack is released for this purpose. On the other hand, the 45 wires must not be released by the elements 53 too soon, or the slack will be lost by backward creep of the wires through the twister bars toward the place where the elements 53 are contacting with the entering wires and forming 50 the loops or depressed portions. I have found it important to relate the cam tracks 68 and 69 to the positioning means B so that the twist is formed in the mesh wires as the slack between twisters is released by the elements 53. In this 55 way I prevent a backward creep, and make sure that the slack is available for the twist.

I have found that a simple way of mounting the twisters 19 in the recesses 24 is to machine these recesses with a boss 78 coaxial with the recess 60 24. The hub of the twister gear 19 is provided in one face with an opening corresponding in size to the boss 78 for receiving the latter so as to be journaled thereon. This constitutes a simple mounting for the twister gear 19 on the member 65 23 within the recess 24 by what is in effect an integral stud 78.

A fabricating machine organized in accordance with my teaching has the advantage that the wires are laid in the slots of the twister bars 70 without requiring the operation of a separate distributor. The guide surfaces in cooperation with the positioning means bring about automatically the distribution of the wires into the desired zig-zag pattern. The elements of the positioning 75 means interengage with the twister bars so as

to force the wires into the bottoms of the slots. Moreover, the wires are depressed sufficiently so as to produce a loop of slack between twister bars. This slack is taken up in the twisting of the mesh wires, and wear on the machine incidental 5 to creeping of the wires through the machine to the point where the twist takes place is substantially eliminated. Moreover, my invention has the important advantage that it minimizes the danger of excessive tension on the wires when 10 being twisted to form the wire fabric.

A further important feature of my invention is the proper timing of the reciprocation of the rack bars to bring about twisting as the positioning means move out of interengagement with the 15 twister bars and release the loops. My invention, therefore, has the advantage that the wires are under control so that the slack is employed for the desired purpose.

While I have illustrated and described one 20 embodiment of my invention, which embodiment is the one I at present prefer, it will be understood that the invention may be otherwise embodied or practiced within the scope of the following claims.

I claim:

1. In a wire fabric making machine of the type wherein the mesh wires are given a substantially zig-zag pattern for twisting into hexagonal mesh, the combination of twisting devices arranged in transverse rows, and means for positioning the mesh wires in said devices and for depressing the portions of the wires intermediate the rows into loops of slack between the twisting 30 devices. 35

2. In a wire fabric making machine of the type wherein the mesh wires are brought together and twisted to form hexagonal mesh, the combination of twisting devices arranged in transverse rows, means for positioning the mesh wires in said 40 twisting devices so as to provide loops of slack between the twisting devices and for thereafter releasing the wires, and means operating in timed relation with said first-mentioned means for rotating the twisting devices as the mesh wires are 45 released by said first-mentioned means.

3. In a wire fabric making machine, the combination of twisters of the slotted gear type arranged in transverse rows, guides having surfaces for guiding mesh wires into the slots of 50 said twisters, and wire engaging elements extending lengthwise of the rows for pushing the wires along said guide surfaces into the slots of said twisters and for depressing the portions of the wires intermediate the rows so as to provide 55 slack between the twisters.

4. In a wire fabric making machine, the combination of twisters of the slotted gear type arranged in transverse rows with the twisters in staggered relationship, guides having inclined 60 surfaces for guiding mesh wires into the slots of said twisters in a zig-zag pattern, wire engaging elements extending lengthwise of the rows for pushing the wires along said guide surfaces into the slots of said twisters and for deflecting 65 the portions of the wires intermediate the rows into loops of slack between the twisters, and means for adjusting said elements to vary the amount of slack provided thereby.

5. In a wire fabric making machine, the combination of twisters of the slotted gear type arranged in transverse rows, guides having surfaces for guiding mesh wires into the slots of 70 said twisters, wire engaging elements extending lengthwise of the rows and operable in coopera- 75

tion with said guide surfaces to position the wires in said twisters, said elements being operable to deflect the portions of the wires intermediate the rows into loops of slack between the twisters 5 and to thereafter release the wires, and means operating in timed relation with said elements for rotating the twisters as the wires are released by said elements.

6. In a wire fabric making machine, in combination, twisters of the slotted gear type arranged in transverse rows with the twisters in staggered relationship, guides having inclined surfaces for guiding mesh wires into the slots of said twisters in a zig-zag pattern, wire engaging elements extending lengthwise of the rows operable to push the wires along said guiding surfaces into the slots of said twisters and to depress the portions of the wires intermediate the rows into loops of slack between the twisters, said 10 elements being thereafter operable to release the wires, means for adjusting said elements to vary the amount of slack in said loops, and actuating means operating in timed relation with said elements for rotating the twisters as said elements 15 release the wires.

7. In a wire fabric making machine of the type wherein the mesh wires are given a substantially zig-zag pattern for twisting into hexagonal mesh, in combination, twisting devices arranged in transverse rows, a capstan cooperating with bights or turns of mesh wires for frictionally feeding said wires to said twisting devices, and means for positioning the mesh wires in said twisting devices.

8. In a wire fabric making machine of the type wherein the mesh wires are given a substantially zig-zag pattern for twisting into hexagonal mesh, the combination of twisting devices arranged in transverse rows, means frictionally engaging the mesh wires for feeding said wires to said twisting devices, and means for positioning the mesh wires in said twisting devices and for deflecting the portions of the wires intermediate the rows so as to provide slack between the twisting 30 devices.

9. In a wire fabric making machine, the combination of twisters of the slotted gear type arranged in transverse rows, a capstan cooperating with bights or turns of mesh wires for frictionally feeding said wires to said twisters, guides having surfaces for guiding the mesh wires into the slots of said twisters, and wire engaging elements extending lengthwise of the rows for pushing

them along said guiding surfaces into the slots of said twisters and for providing loops of slack between the twisters.

10. The combination as defined in claim 9 in which the wire engaging elements are adjustable 5 for varying the amount of slack in the loops between the twisters.

11. In a wire fabric making machine of the type wherein the mesh wires are given a substantially zig-zag pattern for twisting into hexagonal mesh, the combination of twisting devices arranged in transverse rows, guides having surfaces for guiding the mesh wires into said devices, wire engaging elements extending lengthwise of the rows for pushing the wires along said 10 guide surfaces into the twisting devices and for depressing the portions of the wires intermediate the rows so as to provide slack between said devices, and means for adjusting said wire engaging elements to vary the amount of slack provided 15 between said devices.

12. In a wire fabric making machine of the type wherein the mesh wires are given a substantially zig-zag pattern for twisting into hexagonal mesh, the combination of twisting devices arranged in transverse rows, guides having surfaces for guiding the mesh wires into said devices, and means for pushing the mesh wires along said guide surfaces into said devices and for providing loops of slack between said devices comprising endless carriers and wire engaging elements thereon extending lengthwise 20 of the rows and intermeshing therewith.

13. The combination defined in claim 12 in which the endless carriers are adjustable toward 25 and from the twisting devices to vary the amount of slack provided between said devices.

14. In a wire fabric making machine of the type wherein the mesh wires are given a substantially zig-zag pattern for twisting into hexagonal mesh, the combination of twisters of the slotted gear type arranged in transverse rows with the twisters in staggered relationship, means frictionally engaging the mesh wires for feeding 30 said wires to said twisters, guides having surfaces for guiding the mesh wires into the slots of said twisters, and wire engaging elements extending lengthwise of the rows for positioning said wires in said twisters and for deflecting the portions 40 of the wires intermediate the rows so as to provide slack between the twisters.

CARL W. HOLMQUIST.
